UNITED STATES PATENT OFFICE.

JOHN W. ALLEN, OF VISALIA, CALIFORNIA.

MAIL-BOX.

1,237,739.

Specification of Letters Patent. Patented Aug. 21, 1917.

Application filed August 9, 1916. Serial No. 114,031.

To all whom it may concern:

Be it known that I, JOHN W. ALLEN, a citizen of the United States, residing at Visalia, in the county of Tulare and State of California, have invented a new and useful Mail-Box, of which the following is a specification.

This invention relates to mail boxes particularly designed for use along rural delivery routes, although it is to be understood that the same can be employed wherever desired.

One of the objects of the invention is to provide a simple form of box which will fully protect the contents thereof from rain and snow and which automatically closes after mail has been placed therein or removed therefrom.

A further object is to provide a box which is cheap to manufacture and can be easily set up for use, the same being simple, durable and efficient.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—

Figure 1 is an elevation of the mail box.

Fig. 2 is a plan view thereof, a portion being shown in section.

Fig. 3 is a section on line 3—3 Fig. 2.

Referring to the figures by characters of reference 1 designates a top strip forming the upper portion of a bracket and designed to be secured to a post 2 or other suitable support. An angular strip 3 is secured to this top strip and arranged thereunder and forms the lower portion of the bracket. Arranged between the strips 1 and 3 is a cylindrical container 4 having a conical top 5 and a flat bottom 6. An elongated bearing stud 7 extends downward from the center of the bottom of the container and is slidably and revolvably mounted within the strip 3 of the bracket. A bearing member 8 is slidably and revolvably mounted within the top strip 1 and is fixedly connected to

the top 5. This bearing member has a radial arm 9 at its upper end which is normally supported above and close to the strip 1 and preferably carries an anti-friction roller 10. Extending from the free end portion of the strip 1 is a lifting arm 11 which is concentric with the bearing members 8 and is inclined upwardly toward its free end, it being preferably formed with a terminal stop 12. This arm 11 is so located that when the receptacle or container 4 is rotated the roller 10 will travel along the arm 11 and thus cause the container to be lifted out of its normal position.

Secured to the wall of the container close to the lower edge of an opening 13 therein is a guide strip 14 the upper or free longitudinal edge of which is spaced from the wall of the container to provide a guideway 15 as indicated particularly in Fig. 3. This guide strip 14 may be made integral with the inner edge of a plate 16 forming a shelf extending outwardly from the container and at one end of this shelf is provided an outstanding wing 17 which extends along one of the side edges of the opening 13 to the top thereof.

Fixedly connected to the strip 13 close to the support 2 is an arcuate closure 18. This closure is disposed with its greater portion concentric with and close to the wall of the container 4, and when the roller 10 is located in its normal position at the bottom of the inclined arm 11, the wing 17 will engage the free end of the closure 18, while a portion of the lower edge of the closure will be seated in the space 15. When it is desired to place articles within or remove them from the container, the wing 17 is shifted toward the left in Fig. 1. This will cause the container to rotate and at the same time the roller 10 will travel along the arm 11, thereby raising the container out of its normal position. As the closure 18 is stationary, this movement will result in the exposure of the opening 13. Consequently articles can be placed in or removed from the container and as soon as the wing 17 is released, the container will gravitate to its normal position, roller 10 at this time traveling down along the arm 11 so that during the gravitation of the container the same will be rotated to bring the wing 17 against the end of the closure 18. Consequently the container will be automatically closed when released.

What is claimed is:—

1. A mail box including a revoluble and vertically slidable container, an aperture in the wall thereof, a fixed closure having a portion thereof concentric with the wall of the container, a support, and coöperating means upon the support and container for lifting the container during the rotation thereof out of normal position.
- 10 2. A mail box including a support, a revoluble container carried thereby and slidable vertically, said container having a peripheral opening, a closure fixedly connected to the support and having a portion thereof concentric with the container and normally closing the opening, a guide member upon the container and slidably engaging the support, and coöperating means upon the support and the container for automatically elevating the container when rotated out of normal position.
- 15 3. A mail box including a support, a revoluble container carried thereby and slidable vertically, said container having a peripheral opening, a closure fixedly connected to the support and having a portion thereof concentric with the container and normally closing the opening, a guide member upon the container and slidably engaging the support, coöperating means upon the support and the container for automatically elevating the container when rotated out of normal position, a shelf outstanding from the guiding means, and means carried by the shelf and coöperating with the closure for limiting the movement of the container when brought to normal position.
- 20 4. A mail box and the like, including a support, a cylindrical container mounted for rotation therein and slidable vertically, said container having a peripheral opening, a guide upon the container and adjacent the opening, a fixed closure having a portion concentric with the container and slidably engaging the guide, an arcuate lifting arm carried by the support, means revoluble with the container and movable along said arm for elevating the container during the rotation thereof out of normal position.
- 25 5. A mail box and the like, including a support, a cylindrical container mounted for rotation therein and slidable vertically, said container having a peripheral opening, a guide upon the container and adjacent the opening, a fixed closure having a portion concentric with the container and slidably engaging the guide, an arcuate lifting arm carried by the support, means revoluble with the container and movable along said arm for elevating the container during the rotation thereof out of normal position, a shelf outstanding from the guide and adjacent the bottom of the opening, means carried by the shelf and coöperating with the closure for limiting the movement of the container to its normal position.

In testimony that I claim the foregoing as my own, I have hereto affixed my signature in the presence of two witnesses.

JOHN W. ALLEN.
